FRANCIS M. BARTON, OF CHICAGO, ILLINOIS.

METALLIC REINFORCEMENT FOR CONCRETE STRUCTURES.

1,293,301.

Specification of Letters Patent. Patented Feb. 4, 1919.

Application filed June 24, 1918. Serial No. 241,511.

To all whom it may concern:

Be it known that I, FRANCIS M. BARTON, a citizen of the United States, and a resident of Chicago, in the county of Cook and State 5 of Illinois, have invented certain new and useful Improvements in Metallic Reinforcement for Concrete Structures, of which the following is a full, clear, and exact description.

The invention relates to metallic reinforcement for concrete structures and its object is to provide improved devices adapted to be applied to crossed reinforcing bars or rods to conjointly secure them together at 15 their crossing points and act as spacing devices between adjacent rods running in the same direction or crossing another rod.

The invention consists in the several novel features hereinafter set forth and more particularly defined by claims at the conclusion hereof.

In the drawings: Figure 1 is a side elevation of metallic reinforcement embodying one form of the invention. Fig. 2 is a plan. Fig. 3 is a perspective. Fig. 4 is a side elevation. Fig. 5 is a plan and Fig. 6 is a perspective of another form of the invention. Fig. 7 is a detail of another modification.

In reinforced concrete structures, it is now the practice to use wires to bind crossed reinforcing rods together at the crossings in floor or column construction. In this practice, the operator is relied upon to properly space the reinforcing rods running the same 35 general direction from one another, and owing to the character of the labor employed in this work, it frequently occurs that the rods are not equidistantly or properly spaced and as a result, the reinforcement 40 will not be as efficient as desired. To meet these conditions, the present invention contemplates the provision of clips of wire which are adapted at one point to be lapped around two crossed rods to secure them together, and an extension or extensions on 45 the clip are adapted to engage a rod at the next crossing in such manner that the parallel rods will, of necessity, be properly spaced apart as determined by these extensions, by the workmen.

In the form of the invention shown in Figs. 1, 2 and 3, each clip comprises a loop 8 adapted to pass around one side of a longitudinal reinforcing rod 10 and opposing or 55 coacting loop portions 11 adapted to pass around a crossing or transverse rod 12, arms

or members 13 adapted to extend from the transverse rod 12 to the next transverse rod 14 of those to be secured to the longitudinal rod 10 and hooks 15 on the ends of the members 13 which are adapted to engage the rod 14 and space it the correct distance from the rod 12. These clips are formed of spring wire so that the loop portions 8 and 11 will serve to clamp rods 10 and 12 together, and so that the hooks 15 can be sprung downwardly, as shown by dotted lines in Fig. 1, to permit the rod 14 to be slipped into place for engagement by the hooks. These clips are secured on serially alined longitudinal rods 10, as shown in Figs. 1 and 2, and a loop 8 of one clip is adapted to pass around the outer sides of the hooks 15 of the next clip.

This construction exemplifies a clip which may be readily formed of wire, which is adapted to be looped around one pair of crossed rods at one crossing, and is provided with an extension or member adapted to engage another crossing rod at a second crossing. In other words, the clip serves as a combined securing device and spacer, and by applying these clips serially to the crossings of reinforcing bars, the crossing rods will all be secured together in definitely spaced relation and this result is attained without notching any of the reinforcing rods.

In Figs. 4, 5, and 6, a modification is shown in which the clip is provided with a loop 8^a adapted to pass under a longitudinal rod 10, a pair of opposed or coacting loops 11^a adapted to engage the transverse rod 12 and an extension or member 13^a on one of the loops 11^a which is provided with a loop 17 to hold a transverse rod 12^a properly spaced from the rod 12 and a hook 15^a at its outer end adapted to pass under a third transverse rod 14^a and an extension 18 which is reverted, as at 19, to form a support for holding the reinforcing rods spaced above a 100 staging. It will be understood that rod 14^a will be held at the proper point along the rod 10 by the hook 15^a and that the loop 8^a of the next clip in the series will serve to lock rod 14^a in place. This modified form 105 of clip is also formed of spring or resilient wire, exemplifies a clip adapted for use in connection with crossed reinforcing rods in concrete structures, whereby the rods at one crossing will be secured together and where- 110 by a plurality of rods at adjacent crossings will be properly spaced apart.

In the form of the invention shown in Figs. 1, 2 and 3, each clip comprises a loop 8 adapted to pass around one side of a longitudinal reinforcing rod 10 and opposing or 55 coacting loop portions 11 adapted to pass around a crossing or transverse rod 12, arms

In the form of the invention shown in Fig. 7, the loops 11^b are adapted to extend over a plurality of transverse rods which is sometimes desirable in column reinforcements at the terminals of helical coils, or in any other place where parallel lapping rods are to be secured together.

The invention is not to be understood as restricted to the details set forth, since these 10 may be modified within the scope of the appended claims, without departing from the spirit and scope of the invention.

Having thus described the invention, what I claim as new and desire to secure by Letters Patent, is—

1. In reinforcement for concrete structures, the combination of crossed bars and clips separate from the rods, provided with loops to extend around and secure a plurality of crossed rods together at one crossing and with an extension provided with means to space a crossing rod at another crossing.

2. In reinforcement for concrete structures, the combination of crossed bars and a clip separate from the rods, provided with a loop to extend around a longitudinal rod and with a plurality of opposed loops adapted to pass around a transverse rod and secure the crossed rods together at one crossing and with an extension having means for spacing a transverse rod at another crossing.

3. In reinforcement for concrete structures, the combination of crossed bars, and a clip separate from the rods, provided with a

loop to extend around a longitudinal rod and opposing loops to extend around a transverse rod to secure crossed rods together at one crossing and with an extension provided with a hook to engage a transverse rod at another crossing, the hook being formed in opposing relation to the loops for the first mentioned transverse rod.

4. In reinforcement for concrete structures, the combination of crossed bars and clips separate from the rods, provided with loops adapted to extend around and secure the plurality of crossed rods at one crossing, with an extension having means to space a crossing rod at another crossing and with an extension to form a support for reinforcement.

5. In reinforcement for concrete structures, the combination of crossed bars and clips separate from the rods, provided with loops to extend around and secure together a plurality of crossed rods at one crossing and with an extension having means to space a crossing rod at another crossing, the loops and extension of serial clips being interfitting.

6. In reinforcement for concrete structures, the combination of crossed bars and clips separate from the rods, provided with loops to extend around and secure a plurality of crossed rods at one crossing and with an extension having a hook for spacing a crossing rod at another crossing, the loop of one clip being formed to the end around the extension on another clip.

FRANCIS M. BARTON.
